INSPECTION MIRROR

Robert F. Buttles, Torrance, and William B. Sponsler,
Rolling Hills, Calif., assignors to Northrop Corporation,
Beverly Hills, Calif., a corporation of California

Filed Mar. 29, 1960, Ser. No. 59,931

Term of patent 14 years

(Cl. D54—13)

Figure 1 is a perspective view of an inspection mirror, showing our new design.

Figure 2 is a side elevational view

Figure 3 is an end elevational view as seen from the left of Figure 1.

Figure 4 is a plan view of the mirror head with portions of the design omitted for convenience of illustration.

We claim:

The ornamental design for an inspection mirror, substantially as shown.
